UNITED STATES PATENT OFFICE.

ISIDOR KITSEE, OF PHILADELPHIA, PENNSYLVANIA.

PROJECTING APPARATUS.

1,070,699.

Specification of Letters Patent.

Patented Aug. 19, 1913.

Application filed January 26, 1912. Serial No. 673,579.

To all whom it may concern:

Be it known that I, ISIDOR KITSEE, citizen of the United States, residing at Philadelphia, in the county of Philadelphia and 5 State of Pennsylvania, have invented certain new and useful Improvements in Projecting Apparatus, of which the following is a specification.

My invention relates to an improvement 10 exhibiting photographic pictures.

It is unnecessary here to relate all the 15 achievements or experiments made in photography with the aid of colored screens commonly called "color photography". It is only necessary to state that all results 20 so far have this disadvantage that the different color-rays are abruptly brought in view of the picture to be taken and abruptly taken therefrom and rays of other colors abruptly 25 substituted therefor.

With the arrangements of today, the gradual rise and fall of the intensity of one 25 color ray and its merging in the succeeding color-ray is impossible and it is the aim of 30 my invention to enable persons versed in the art to so adjust the source of rays that the above disadvantage is entirely eliminated.

My invention also contemplates the exhibiting of pictures in a manner so that the 35 advantages formerly gained should also be maintained during the time of exhibiting the same.

For the purpose of illustrating one form 40 my invention may take, I have reference to 35 the accompanying drawing, in which—

Figure 1 is a perspective view of a projecting machine illustrating here the light and film mechanism and Fig. 2 is a diagram of the electrical circuit.

40 Persons versed in the art of electric science well understand that in the rapid lighting and extinguishing of electric lamps, the glow of the electrodes or filaments still persists—to a certain extent—even after 45 the circuit is broken and when a series of lamps are successively connected to and disconnected from a circuit in rapid succession, the rays of the preceding and cut-out lamp will always commingle with the rays 50 of the lamp following, for a short period. As is known to those skilled in the art of electric lamps, the time interval of "after glow" that is the time of glow after the current has been reduced or cut off, can be 55 made anything desired, within limits. This

for the reason that, in the case of incandescent lamps for example, the filaments may be of different sizes or thicknesses, so that they hold their heat for different lengths of time, and therefore the after glow persists 60 for different lengths of time.

I have here shown incandescent lamps as the source of light. In present days, where the art of metallic filaments is so well developed, such lamps may be used to advantage, but it is obvious that other types may be used. As is self-evident, in the type shown in the drawing, that is, incandescent type, the globe has to be colored to suit requirements.

When, with the arrangement as illustrated, the pictures are projected in such rapid succession as is required for the purpose of moving pictures, then the advantage of my invention is most apparent, for the 70 reason that here the merging of the rays of the different colors, following each other in rapid succession, will be most apparent in the resultant effect of the picture. A second advantage of my invention lies in the fact 75 that I project through each picture unit of a certain color value light of the color of such color value derived from a periodically energized source of light of such color as distinguished from the use of a continuously 80 operating source of light projected through different color screens in succession.

Coming now to the projecting of photographic pictures in the well known art of moving pictures, which is clearly illustrated 90 in Figs. 1 and 2, in Fig. 1, a' is the projection apparatus, having a suitable lens b' . c' , d' and e' are three sources of light, of which c' may be red, d' yellow and e' blue. These lights are here shown of the well 95 known type of incandescent lamps, but it is obvious that here also this type may be replaced by any other suitable type. The film with the pictures thereon is here designated as f' actuated by sprocket g' . This 100 sprocket is adapted to be put in motion with the aid of the shaft j' . On this shaft is positioned the commutator comprising the three conducting segments k' , l' and m' . All of these segments are in electrical contact with 105 the shaft and against this shaft rests the brush p' . The other parts of the commutator consist of the insulating material n' .

The film has thereon a series of picture 110 units, neighboring picture units being of

different color values; and as each picture unit is presented for exposure a source of light of corresponding color is energized.

The *modus operandi* is as follows:—When 5 through the movement of the shaft, the sprocket is moved, thereby bringing to view a picture, then one of the commutator-segments is brought in contact with one of the brushes, thereby connecting one of the lights into the circuit, here shown as an incandescent lamp. It is now supposed that during one revolution of the sprocket wheel three pictures are brought successively to view and it is taken for granted that the 10 commutator (positioned on the same shaft) is also making one revolution during one revolution of the sprocket wheel and that thereby successively all of the three segments come in contact with their respective 15 brushes and it is also taken for granted that the first segment closes the circuit including the lamp giving out red rays, the second segment with the lamp giving out yellow rays and the third segment with the lamp giving out blue rays. If now the sprocket 20 wheel rapidly revolves, the resultant effect will not only be a change from one color to a second color, but also a graduation of this change through the persistence of the glow 25 of one lamp at the time that the succeeding lamp commences to give out light rays of its own color. It is obvious that instead of entirely breaking the lamp circuit, a resistance of high value may be thrown in this 30 circuit. This resistance will reduce the flow 35 of current in the circuit to such a minimum that the lamp will only slightly glow and the degree of this glow can then be regulated and is in inverse proportion to the value of 40 the resistance. Instead, therefore, of extinguishing the light, the intensity of the light may only be reduced. In the case 45 where the glow of one lamp persists until or after the beginning of the glow of the next lamp the color values of the correspondingly 50 presented picture units are correspondingly modified by the picture taking or camera apparatus.

Having now described my invention, what 55 I claim as new and desire to secure by Letters Patent is:—

1. The combination with a film comprising a plurality of picture units, of a plurality of sources of light of different colors, 55 means for moving said film with respect to said sources of light, and means for extinguishing and energizing said light sources in succession, one light source continuing to produce light an interval of time after the 60 beginning of light delivery by a succeeding source of light.

2. In apparatus of the character described, a plurality of electric lights, each producing light of a color different from the colors of 65 the other electric lights, a moving picture

film, means for advancing said film, and means operatively related with said film advancing means for controlling said electric lights in a predetermined order.

3. In apparatus of the character described, 70 a plurality of electric lamps, each producing light of a color different from the colors produced by the other electric lamps, a moving picture film, and means for energizing said electric lamps in succession in synchronism with the movement of said film. 75

4. In apparatus of the character described, the combination with a moving picture film, 80 of a plurality of stationary electric lights, each adapted to produce light of a color different from the colors produced by the other electric lights, and means for energizing said electric lights in succession in synchronism with the movement of said film. 85

5. In apparatus of the character described, 85 a picture film comprising a plurality of picture units, neighboring picture units having different color values, a plurality of sources of light, each source delivering light 90 of a color different from the light delivered by the other sources, means for rendering said sources active in synchronism with the movement of the film, each picture unit of said film being subjected to light of a color 95 the same as the color value of said picture unit.

6. In apparatus of the character described, a moving picture film comprising a plurality of picture units, neighboring picture units having different color values, a plurality of 100 electric lights, each delivering light of a color different from the color delivered by the other electric lights, means for energizing said electric lights in step with the movement of said film, each picture unit being 105 subjected to a color of light the same as the color value of said picture unit.

7. In apparatus of the character described, a moving picture film, means for moving said film, a plurality of electric lights, each 110 delivering a light of a color different from the light delivered by the other electric lights, and switching means moving in definite relation with respect to said film feeding means for energizing said electric lights 115 in succession.

8. In apparatus for projecting moving pictures in substantially natural colors without the use of moving color screens, the combination with a moving picture film, of a 120 plurality of stationary sources of light, each source delivering a color of light different from the color of light delivered by the other source, means for moving said film, and means movable in definite relation with said 125 film moving means for rendering said light sources active in succession and in step with the movement of said film.

9. In apparatus for projecting moving pictures in substantially natural colors with- 130

- out moving color screens, the combination with a moving picture film, of means for moving said film, a commutator moving in definite relation with respect to said film 5 moving means, and a plurality of electric lights controlled in succession by said commutator, each electric light delivering light of a color different from the color delivered by the other electric lights.
- 10 10. The method of projecting moving pictures in substantially their natural colors, which consists in rapidly moving a series of picture units, neighboring picture units of the series differing from each other in 15 their color values, energizing a plurality of light sources in succession and at a rate corresponding with the rate of movement of the picture units, each source of light delivering a light of color different from the colors delivered by the other sources of light, and subjecting each picture unit to a light of color corresponding with the color value of 20 that picture unit.

11. The method of projecting moving pictures in substantially their natural colors, 25 which consists in rapidly moving a series of picture units, neighboring picture units of the series differing from each other in their color values, energizing a plurality of light sources in succession and at a rate corresponding with the rate of movement of the picture units, each source of light delivering a light of color different from the colors delivered by the other sources of light, and subjecting each picture unit to a light of 30 color corresponding with the color value of that picture unit, and causing the light from each source to persist for a predetermined interval of time and to mingle with the light delivered by another source. 35

In testimony whereof I affix my signature in presence of two witnesses.
